UNITED STATES PATENT OFFICE.

AUSTIN A. RILEY, OF LEAVENWORTH, KANSAS.

STEAM WASHING-MACHINE.

1,177,807.

Specification of Letters Patent.

Patented Apr. 4, 1916.

Application filed October 30, 1914. Serial No. 869,429.

To all whom it may concern:

Be it known that I, AUSTIN A. RILEY, a citizen of the United States, residing at Leavenworth, in the county of Leavenworth and State of Kansas, have invented new and useful Improvements in Steam Washing-Machines, of which the following is a specification.

This invention relates to a washing machine and more particularly to the class of steam boilers for washing clothes.

The primary object of the invention is the provision of a boiler of this character wherein on the placing of clothes therein the same will be thoroughly washed without damage thereto, the washing medium being circulated within the boiler in a novel manner so as to penetrate the clothes for removing all dirt therefrom thereby obviating the necessity of labor for agitating the clothes as is usual.

Another object of the invention is the provision of a boiler of this character wherein the water therein will be spread in a novel manner and circulated through the clothes to be washed so that the same will be rendered clean before their removal from the boiler thereby avoiding the necessity of hand labor in the rubbing of the clothes or the use of an ordinary washing machine.

A further object of the invention is the provision of a boiler of this character which is simple in construction, thoroughly reliable and efficient in its purpose, and inexpensive in manufacture.

With these and other objects in view the invention consists in the features of construction, the combination and arrangement of parts, as will be hereinafter fully described, illustrated in the accompanying drawing and pointed out in the claims hereunto appended.

In the drawings: Figure 1 is a vertical longitudinal section view through a boiler constructed in accordance with the invention. Fig. 2 is a sectional view of the line 2—2 of Fig. 1. Fig. 3 is a sectional view on the line 3—3 of Fig. 1. Fig. 4 is a perspective view of the percolater.

Similar reference characters indicate corresponding parts of the several views of the drawing.

Referring to the drawings in detail the boiler comprises a hollow body 5 preferably made from block sheet tin, although the same may be made from any other suitable

material and also may be of any required shape. The upper open end of the body 5 is formed with an outwardly curved bead 6 which is reinforced in the usual manner, 60 that is to say by a rigid wire or rod 7 inclosed within the bead. Detachably fitted on the body 5 of the boiler is a removable cover or lid 8 preferably of inverted conical shape and is formed with a depending flange 9 which is adapted to telescope within the upper open end of the body 5 while without this flange 9 is a marginal rim 10 the latter being adapted to rest upon the bead 6 when the cover or lid 8 is placed 70 upon the body 5 of the boiler. Fixed exteriorly on the cover or lid 8 is a loop handle 11 which permits the convenient placing of the lid or cover on the body of the boiler or its removal therefrom.

Formed in the wall of the body 5 spaced from its bottom is a continuous substantially V-shaped groove 12 which is struck inwardly from the said wall to form an internal shoulder 13 on which rests a substantially conical shaped hood 14 having a hollow central column 15 which rises a predetermined distance within the body 5 and carries at its upper end a conical shaped cap 16 formed with a central nipple 17 85 through which is passed a vertical pipe 18 which rises centrally from a conical shaped percolator body 19 forming a heating chamber 20, the said body 19 resting on the bottom of the boiler. The percolator body 19 is formed with a vertical marginal rim 21 90 formed at intervals with openings 22 to permit water to pass from the body 5 of the boiler into the heating chamber 20 within the percolator body 19 during the washing process. The vertical pipe 18 rising from the percolator body 19 has its upper end extended in close proximity to the apex of the conical shaped cover or lid 8 when placed upon the body 5 of the boiler.

Arranged concentrically about the column 15 of the hood 14 is a ring-like supporting plate 23 the same being formed with legs 24 which rest upon the said hood 14 and this plate is designed to support clothes when placed within the body 5 of the boiler.

Formed in the hood 14 near the marginal edge thereof at intervals are perforations 25 which allow the water to pass downwardly beneath the said hood 14 during the circulation of the water within the body 5 of the boiler.

Tapped in one end of the body 5 of the boiler is a drain faucet 26 having the usual hand-operated cut-off plug 27 and on the opening of the plug the contents of the 5 boiler can be drained therefrom.

Fixed to the inner surface of the lid or cover 8 centrally thereof is a depending crown ring 28 while also supported by the said lid or cover 8 within the hollow thereof 10 are a series of concentrically arranged truncated conical water spreader rings 29 which are held in their relatively assembled relations through the medium of hanger straps or brackets 30 which connect the said rings 15 29 together at intervals and also connect the outermost ring of the series to the lid or cover so that these rings 29 will be suspended within the said lid or cover and concentrically about the pipe 18 rising from 20 the percolator body 19 on the application of the cover or lid 8 upon the body 5 of the boiler.

Mounted on the outside of the body 5 of the boiler at opposite ends thereof are swinging handles 31 which permit the carrying of 25 the boiler from one point to another.

Formed in the cover or lid 8 is a peep-hole 32 while pivoted on the said lid or cover is a swinging cap 33 which normally closes 30 the peep-hole 32, the cap being formed with a finger lug 34 whereby it may be opened or closed.

The nipple 17 on the cap 16 carried by the central column 15 of the hood snugly fits 35 about the pipe 18 so as to prevent leakage between the latter and the said cap during the circulation of the water within the boiler.

In the operation of the machine or boiler 40 the required amount of water is placed within the body 5 thereof and thereafter the clothes are introduced so that the same will be supported by the plate 23 whereupon the body of the boiler is placed upon a stove 45 so that the water will become heated in the heating chamber 20 within the percolator body 19, thence the water passes upwardly through the pipe 18, breaking at the apex of the cover or lid 8 which causes the water 50 to pass over the series of spreader rings 29 for distributing the hot water evenly over the clothes and carrying the dirt with it as the hot water passes through the clothes returning to the heating chamber 20 through 55 the holes 25 and 22 in the pressure hood 14 and percolator body 19. In this manner the water is circulated within the boiler 5 60 through the clothes for the proper washing and cleansing thereof. The operation of the boiler is continued until the clothes are

thoroughly washed and cleaned, and thereafter the clothes are removed from the boiler.

From the foregoing it is thought that the construction and operation of the invention 65 will be clearly understood and therefore a more extended explanation has been omitted.

What is claimed is:—

1. A boiler of the class described comprising a hollow body, an inverted conical-shaped cover for said body having a depending marginal flange adapted to telescope within the upper open end of the body, the side wall of said body being provided with a groove struck inwardly thereof to 70 form an internal shoulder, a conical-shaped hood resting upon the shoulder and having a central vertical column rising for a distance within the body, a cap on said column and having a central nipple, a reticulated conical-shaped percolator body resting upon the bottom of said body to form a heating chamber, a pipe rising centrally from said percolator body and passed upwardly through the nipple and terminating within 75 the cover, and a ring-like supporting plate concentrically disposed about the column and having legs adapted to rest upon the hood.

2. A boiler of the class described comprising a hollow body, an inverted conical-shaped cover for said body having a depending marginal flange adapted to telescope within the upper open end of the body, the side wall of said body being provided with a groove struck inwardly thereof to 90 form an internal shoulder, a conical-shaped hood resting upon the shoulder and having a central vertical column rising for a distance within the body, a cap on said column and having a central nipple, a reticulated conical-shaped percolator body resting upon the bottom of said body to form a heating chamber, a pipe rising centrally from said percolator body and passed upwardly 95 through the nipple and terminating within the cover, and a ring-like supporting plate concentrically disposed about the column and having legs adapted to rest upon the hood, a depending crown ring mounted within the 100 cover, and a plurality of concentrically arranged truncated conical-shaped water spreader rings fixed within the cover for suspension therefrom.

In testimony whereof I affix my signature 115 in presence of two witnesses.

AUSTIN A. RILEY.
